DESIGN FOR A COMB

Anthony J. Desimone, Lyndhurst, N. J., assignor to Columbia Protektosite Company, Inc., Carl-stadt, N. J., a corporation of New Jersey

Application December 2, 1943, Serial No. 111,884

Term of patent 7 years

To all whom it may concern:

Be it known that I, Anthony J. Desimone, a citizen of the United States and resident of Lyndhurst, in the county of Bergen and State of New Jersey, have invented a new, original, and ornamental Design for a Comb, of which the following is a specification, reference being had to the accompanying drawing, forming a part thereof, and of which Fig. 1 is a side elevation of a comb showing my new design; Fig. 2 is a plan view thereof; Fig. 3 is an end view of the comb; and Fig. 4 is a sectional view taken on line 4—4 of Fig. 2.

The front and back of the comb are identical.

The dominant features of the design reside in the portions shown in full lines.

I claim:

The ornamental design for a comb, substantially as shown and described.

ANTHONY J. DESIMONE.
